(57) **CLAIM**

The ornamental design for a jewelry connector, as shown and described.

DESCRIPTION

FIG. 1 is a top plan view of a jewelry connector showing the new design;

FIG. 2 is bottom plan view thereof;

FIG. 3 is a left elevational view thereof;

FIG. 4 is a right elevational view thereof;

FIG. 5 is a front elevational view thereof; and,

FIG. 6 is a rear elevational view thereof.

In the drawings, the broken lines shown in FIG. 1 depict unclaimed subject matter only and form no part of the claimed design.
